DEVICE FOR REPRODUCING LETTERS,
FIGURES, OR OTHER CHARACTERS

Charles H. Benedict, Brooklyn, N. Y.

Application July 25, 1939, Serial No. 286,493

9 Claims. (Cl. 33—23)

This invention relates to devices for reproducing letters, figures or other characters.

An object of the invention is to provide a device which will enable anyone to reproduce letters, figures and characters in any desired order or sequence without any special artistic or lettering skill on the part of the operator, and to permit the form and outline of such letters or characters to be varied at will as to height and width, either separately or together within the range of the device. With my improved device any series of letters or characters may be reproduced in various heights and widths from the same guide characters by simple adjustments. A further object of this invention is to provide a device of the character described in which the guide characters are in fixed position, so that any selected character may be reproduced at any time or in any sequence without moving or positioning the guide characters, thereby permitting the character selected to be reproduced rapidly and accurately.

A still further object of this invention is to provide a device of the character described, having means for varying the width of the reproduced letters independently of the height of the letters or characters, so that any line of characters may be longer or shorter, as desired, by a simple adjustment, whereby lines of characters may be lengthened or shortened to fill any desired space within their limitations and producing a neat and artistic effect.

In accordance with the invention, the guide characters are grooved in a plate or panel mounted on the device, the guide character plates being readily removable and interchangeable, whereby different series of characters may be used without any other adjustment than changing the character plates.

Still another object of this invention is to provide a strong, rugged and compact device of the character described, comprising few and simple parts which shall be relatively inexpensive to manufacture, easy to adjust and manipulate, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is

shown one of the various possible illustrative embodiments of this invention,

Fig. 1 is a top plan view of a device for reproducing letters, figures or characters, embodying the invention;

Fig. 2 is a cross-sectional view taken on line 2—2 of Fig. 1;

Fig. 3 is an end view of the device with parts in cross-section;

Fig. 4 is a cross-sectional view taken on line 4—4 of Fig. 1;

Fig. 5 is a cross-sectional view taken on line 5—5 of Fig. 1;

Fig. 6 is a cross-sectional view taken on line 6—6 of Fig. 1;

Fig. 7 is a top plan view of the character plate and the transparent panel formed with openings to receive a pointed element projecting into the groove characters of the character plate;

Fig. 8 is a cross-sectional view taken on line 8—8 of Fig. 7;

Fig. 9 is a partial, top plan view similar to Fig. 7, and showing the pointer in one position;

Fig. 10 is a view similar to Fig. 9, but showing the pointer in another position; and

Fig. 11 is a cross-sectional view taken on line 11—11 of Fig. 10.

Referring now in detail to the drawings, 10 designates a table or base on which is placed a sheet 11 on which letters or characters are to be reproduced. The reproduction is performed by means of a device 12 embodying the invention and placed on the sheet 11.

The device 12 comprises a flat, horizontal base plate 14 of generally rectangular shape having a pair of downwardly extending curved projections 15 adjacent its lower edge 16, contacting the sheet 11 to space the base plate from said sheet.

The base plate 14 is furthermore formed adjacent the upper edge 17 thereof with a plurality of spaced, upstanding, screw threaded bosses 18, formed with central through openings 19. Screwed to the bosses 18 are caps 20 each formed with a central opening 21. Extending through each opening 21 is a stem 22 of a plunger 23. Each plunger 23 has a head 24 at its lower end contacting the sheet 11. Interposed between the head of the plunger and the inner side of the cap 20, and surrounding the stem 22, is a coil spring 25. The upper end of the stem 22 is provided with a head 26.

It will now be noted that the spring 25 presses the head 24 against the sheet to raise the base plate. Pressure on the base plate, however, will

compress the spring 25 to bring the upper edge of the base plate closer to the sheet 11.

On the upper surface of the base plate is a longitudinal dove-tailed upwardly extending 5 guide 30, parallel to the edge 16 of said base plate. The upper surface of the base plate is formed with a rectangular depression 30a located between the guide 30 and the edge 17 of the base plate, and adjacent a side edge 17a of said base 10 plate.

Slidably mounted on the guide 30 is an L-shaped member 31, having a portion 32 forming with a dove-tailed groove 33 to receive the guide 30. Extending from the portion 32 of member 15 31 is an arm 36 perpendicular to the edge 16 of the base plate and spaced somewhat above the upper surface of the base plate.

Slidably mounted on the arm 36 is a sleeve 38 formed with a longitudinal flange 39. Screwed 20 to the flange 39, as by screws 40, is a transparent plate 42, adapted to cover the depression 30a in the base plate. The plate 42 is formed with a plurality of tapered through openings 43 for the purpose hereinafter appearing.

25 Mounted within the depression 30a of the base plate, is a character plate 45 formed in its upper surface with a plurality of grooved letters or characters 46. There is preferably one opening 43 above each character 46 in the base plate.

30 Attached to the outer end of arm 36 is a stop member 38a, to limit sliding movement of member 38 in one direction.

Slidably mounted on the guide 30 is a member 50, having a portion 51 formed with a dove-tailed groove to receive said guide. Extending 35 from the portion 51 of member 50 is an arm 53, parallel to the arm 36 of member 31, and likewise somewhat spaced above the base plate. Slidably mounted on the arm 53 is a member 55 having 40 a sleeve portion 56 receiving said arm. Fixed to the outer end of arm 53 is a stop 53a, to limit sliding movement of member 55 in one direction.

Extending from sleeve 56 are a pair of parallel 45 brackets 58 supporting a guide rod 59, parallel to said sleeve. Extending upwardly from the sleeve 56 are a pair of brackets 60 supporting a transverse pin 61. Pivotally mounted on the pin 61 is an arm 62 having an inclined sleeve 63 at its outer end to receive a lettering pen 64. The 50 pen 64 projects downwardly towards the sheet of paper 11. The arm 62 is formed with a screw threaded opening 66 to receive a screw 67 contacting the upper surface of the sleeve to limit the downward movement of said arm about the pivot 55 pin for adjusting the position of the penpoint relative to the sheet of paper 11. The arm 62 may be fixed to the pin 61 by a set screw 69 adapted to contact the pin 61.

For the purpose hereinafter appearing, the 60 base plate is provided with a pivot pin 70 adjacent the upper edge 17 thereof and the side edge 17b. Pivoted to the pivot 70 is an arm 71. On the pivot pin 70 is a torsion spring 70a tending 65 to move the arm 71 in a clockwise direction, looking at Fig. 1 of the drawings. Interconnecting the lower end of the arm 71 with member 38, is a link 73. Slidably mounted on arm 71 is a sleeve 76 provided with a set screw 77 to fix the sleeve in any adjusted position on said arm.

70 Pivoted to the sleeve 76, as at 78, is a sleeve 80. Slidably extending through the sleeve 80 is a strip 81 adapted to be fixed to the sleeve 80 in any desired position by a set screw 83. Attached to the outer end of the strip 81, as by screw 75 85, is a sleeve 86 slidably receiving the guide rod

59. A set screw 88 on sleeve 86 serves to fix said sleeve to the guide rod in any desired adjusted position.

Slidably mounted on the link 73 is a sleeve 90, adapted to be fixed to said link in any desired 5 adjusted position by a set screw 91. Interconnecting the sleeve 90 with an ear 92 on member 55 is a link 94.

The operation of the device will now be described: 10

The strip 81 may be adjusted on arm 71 and 15 guide rod 59. The member 51 may be slidably moved toward or away from the pivot 70, first loosening the set screws 77 and 88, and then tightening the same.

To reproduce any of the letters or characters 20 46, there is inserted through any suitable opening 43 in the transparent plate 42, a pointed instrument 100. The point of the instrument projects into the selected character. The instrument 25 is then moved to trace the grooved character 46, while the base plate is pressed downwardly to compress the spring 25 for bringing the point of the pen against the paper 11. As the tool traces the character or letter 46, member 31 will slide 30 on the guide 30 and member 38 will slide on the arm 36. This motion is transmitted through the links 73 and 94, the arm 71 and strip 81, to the pen which reproduces the letter on sheet 11. The character plate 45 may be readily replaced. 35

Movement of member 81 further from the pivot 70 increases the horizontal movement of the pen-point, thereby increasing the width of the character traced. Moving of the link 94 further from the left end of the link 73, increases the height 35 of the characters traced by the pen, relative to the height of the guide characters 46 of the character plate.

It will now be understood that the instrument 40 100 may be moved from one opening 43 to another for tracing different characters selected without positioning or moving the guide characters from usual fixed position on the base plate.

It will also now be understood that a great 45 number of variations in height and width on individual characters may be readily made from a single set of guide characters.

It will thus be seen that there is provided a device in which the several objects of this invention are achieved, and which is well adapted to meet the conditions of practical use. 50

As various possible embodiments might be made of the above invention, and as various changes might be made in the embodiment above 55 set forth, it is to be understood that all matter herein set forth or shown in the accompanying drawings is to be interpreted as illustrative and not in a limiting sense.

Having thus described my invention, I claim 60 as new and desire to secure by Letters Patent:

1. A device of the character described comprising a base plate, a longitudinal guide fixed thereon, a character plate mounted on said base plate and having grooved letters or characters in 65 the upper surface thereof, a member slidably mounted on said guide and having an arm extending at right angles to said guide, a panel formed with a plurality of perforations slidably mounted on said arm, a second member slidably mounted on said guide and having an arm extending at right angles to said guide, a third member slidably mounted on the last mentioned arm, a pen mounted on said third member, a member pivoted to said base plate and connected 70 75 80 85 90 95 98 99 100 101 102 103 104 105 106 107 108 109 110 111 112 113 114 115 116 117 118 119 120 121 122 123 124 125 126 127 128 129 130 131 by a link to the first member, a sleeve slidably mounted on the pivoted member, means to connect said sleeve with the third member, a sleeve slidably mounted on said link, and a second link interconnecting the last sleeve with the third member.

2. A device of the character described comprising a base plate, a longitudinal guide fixed thereon, a character plate mounted on said base plate and having grooved letters or characters in the upper surface thereof, a member slidably mounted on said guide and having an arm extending at right angles to said guide, a panel formed with a plurality of perforations slidably mounted on said arm, a second member slidably mounted on said guide and having an arm extending at right angles to said guide, a third member slidably mounted on the last mentioned arm, a pen mounted on said third member, a member pivoted to said base plate and connected by a link to the first member, a sleeve slidably mounted on the pivoted member, means to connect said sleeve with the third member, a sleeve slidably mounted on said link, and a second link interconnecting the last sleeve with the third member, said panel being transparent.

3. A device of the character described comprising a base plate, a longitudinal guide fixed thereon, a character plate mounted on said base plate and having grooved letters or characters in the upper surface thereof, a member slidably mounted on said guide and having an arm extending at right angles to said guide, a panel formed with a plurality of perforations slidably mounted on said arm, a second member slidably mounted on said guide and having an arm extending at right angles to said guide, a third member slidably mounted on the last mentioned arm, a pen mounted on said third member, a member pivoted to said base plate and connected by a link to the first member, a sleeve slidably mounted on the pivoted member, means to connect said sleeve with the third member, a sleeve slidably mounted on said link, a second link interconnecting the last sleeve with the third member, said panel being transparent, and a plurality of spring pressed plungers on said base plate projecting below said base plate.

4. Apparatus for reproducing letters comprising a base, a plate mounted thereon and formed with a plurality of grooved letters in its upper face, a fixed guide on said base, a member slidably mounted on said guide, a transparent panel slidably mounted on said member, a reproducing pen linked to said member, said panel being formed with a plurality of perforations, and a plurality of spring pressed members to support said base.

5. A device for reproducing characters comprising a base, a plate mounted thereon and formed with a plurality of grooved characters, a fixed guide on said base, a member slidably mounted on said guide, a panel slidably mounted on said member and formed with perforations and overlying the character plate, a second member slidably mounted on said guide, means to support a reproducing pen slidably mounted on the second member, an arm pivoted at one end to the base and connected by a link to the panel,

said means being connected by a link to said arm and to the first link.

6. A device for reproducing characters comprising a base, a fixed guide on said base, a member slidably mounted on said guide, a panel formed with spaced perforations slidably mounted on said member, a second member slidably mounted on said guide, a sleeve slidably mounted on said second member and formed with a longitudinal rod, means pivoted to said sleeve and supporting a reproducing pen, an arm pivoted at one end to the base, a link interconnecting the other end of said arm with said panel, a sleeve slidably mounted on said arm, a sleeve pivoted to the last mentioned sleeve, a strip extending through said pivoted sleeve, a sleeve on said strip slidably receiving said rod, a sleeve slidably mounted on said link, and a second link interconnecting the last sleeve with the first sleeve.

7. A device of the character described comprising a base plate, a character plate mounted on said base plate, a member slidably mounted on said base plate, a panel formed with a plurality of perforations, slidably mounted on said member, a second member slidably mounted on said base plate, a third member slidably mounted on said second member, a pen mounted on said third member, a member pivoted to said base plate, and connected by a link to said first member, a sleeve slidably mounted on the pivoted member, means to connect said sleeve with the third member, a sleeve slidably mounted on said link, and a second link interconnecting the last sleeve with the third member.

8. A device of the character described comprising a base plate, a character plate mounted on said base plate, a member slidably mounted on said base plate, a panel formed with a plurality of perforations, slidably mounted on said member, a second member slidably mounted on said base plate, a third member slidably mounted on said second member, a pen mounted on said third member, a member pivoted to said base plate, and connected by a link to said first member, a sleeve slidably mounted on the pivoted member, means to connect said sleeve with the third member, a sleeve slidably mounted on said link, and a second link interconnecting the last sleeve with the third member, said panel being transparent.

9. A device of the character described comprising a base plate, a character plate mounted on said base plate, a member slidably mounted on said base plate, a panel formed with a plurality of perforations, slidably mounted on said member, a second member slidably mounted on said base plate, a third member slidably mounted on said second member, a pen mounted on said third member, a member pivoted to said base plate, and connected by a link to said first member, a sleeve slidably mounted on the pivoted member, means to connect said sleeve with the third member, a sleeve slidably mounted on said link, a second link interconnecting the last sleeve with the third member, and a plurality of spring pressed plungers on said base plate, projecting below the latter.

CHARLES H. BENEDICT.
